UNITED STATES PATENT OFFICE

GEORGE McD. JOHNS, OF SAPPINGTON, MISSOURI

REPORT

Application filed May 6, 1927. Serial No. 189,303.

This invention relates generally to ovens or retorts and, more particularly, to a certain new and useful improvement in ovens or retorts especially adapted for use in the carbonization and distillation of materials carrying a percentage of recoverable volatile matter, such as, for instance, cannel and other bituminous coals, lignite, peat, oil-shale, and the like, from which valuable gases and condensable vapors may be driven off under the action of heat and subsequently recovered by suitable means or processes of collection and condensation.

My invention has, among its principal objects, the provision in an oven or retort of the class stated of means for effecting automatic lubrication of movable parts of the apparatus by a novel placement thereof in the vapor-collecting chambers of the oven; of a continuous vapor-collecting chamber or chambers communicating directly with the carbonizing and distilling or vaporizing chamber of the oven, so arranged that the vapors are drawn off evenly at all points; of convenient and efficient control of the heating of the oven; and of means for effecting elimination of dust troubles; and the improvement and simplification generally of ovens or retorts of the class mentioned.

And with the above and other objects in view, my invention resides in the novel features of form, construction, arrangement, and combination of parts hereinafter described and pointed out in the claims.

In the accompanying drawings—

Figure 1 is a fragmentary view, partly in side elevation and partly in longitudinal vertical section, of the forward portion of the oven or retort;

Figure 2 is a similar view of the rear portion of the oven or retort;

Figure 3 is an enlarged transverse vertical section of the retort, taken approximately on or about the line 3—3, Figure 1;

Figure 4 is a fragmentary view, on an enlarged scale, partly in side elevation and partly in longitudinal vertical section, of the retort, parts being broken away to expose certain details of construction of underlying parts;

Figure 5 is a fragmental side elevation of the oven, showing details of the vertical side reinforcements and supporting uprights of the superstructure;

Figure 6 is a detail fragmental view, partly in side elevation and partly in section, of the conveyor and one of the scraper elements; and

Figure 7 is a plan view of the parts shown in Figure 6.

Referring now more in detail and by reference characters to the drawings, which illustrate a preferred and practical embodiment of my invention, the oven or retort there shown is of the recuperative type and comprises a base or foundation 1 preferably composed of concrete and provided with parallel, spaced, rectangular, longitudinally-extending raised portions or ribs 2, which are capped by inverted channel members 3. Across the channel members 3 are laid and suitably secured transverse floor supports 4 each preferably comprising a pair of angle members disposed with their vertical flanges in abutting relation so as to constitute, in effect, an inverted T-section, on whose horizontal flanges the floor slabs 5 are supported. The slabs 5 are preferably constructed of fire-brick material, and disposed on top thereof is a layer of insulation brick 6, all as best seen in Figures 3 and 4.

At each side of the structure, is an outer base wall 7 of fire-brick material, and intermediate the base walls 7, are longitudinal dividing walls 8 composed of fire-brick or other suitable refractory material preferably of the peculiar tapering cross-section shown. The walls 8 are suitably spaced and afford supports for the floor proper 9 of the combustion or heating-chamber A, the longitudinally extending spaces 10 between the walls 8, which spaces communicate with the chamber A as hereinafter appears, constituting what may be termed "air-recuperating flues", that is to say, the spaces or flues 10 are designed to receive and pre-heat the air before it is admitted to the combustion or heating-chamber A thereabove, the air initially entering the open ends 11, located at the front end of the structure (see Figure 1) of the

spaces or flues 12 formed by the ribs 2 between the foundation proper 1 and the floor-slabs 5, and then flowing from the flues 12 into the flues 10 through communicating passageways 13 located within and adjacent the rear end of the structure, as best seen in Figure 2.

- The floor 9 of the combustion or heating chamber A is constructed generally of fire-brick and is relatively thick as compared with 10 the roof 14 thereof, which latter is preferably composed of slabs of suitable heat-transferring material, such as, for instance, alundum or carborundum tile, special iron, or the like.
- 15 The roof 14 is supported intermediate the side walls of the oven by longitudinally extending division walls 15 composed of fire-brick material and preferably substantially corresponding in cross-section with the floor- 20 supporting walls 8. By the arrangement of the division walls 15, the combustion or heating chamber A is divided to comprise a series of separate longitudinally extending compartments 16.
- 25 The several compartments 16 and the air-recuperating flues 10 are closed at their forward ends by the front wall 17 of the oven (see Figure 1). At the rear end of the oven, the compartments 16 communicate through 30 vertically extending flues 18 provided in the oven rear wall 19 with horizontal base flues 20 (see Figure 2) leading to the usual stack (not shown).

35 Inserted and disposed in the floor 9 of the chamber A, are transversely disposed, special sections or blocks 21 preferably of fire-brick material having a main bore 22 communicating at the side of the oven with a gas-supply pipe 23. In the region of the blocks 21 the 40 floor 9 is transversely channeled, as at 24, and formed in each block 21, is preferably a plurality of vertically disposed jet-orifices 25 communicating with the bore 22 and discharging the supplied gas directly into the 45 channels 24 of the compartments 16 of chamber A. Also provided in the blocks 21 and discharging into the channels 24 for supporting combustion, are ports or ducts 26 leading from the air-flues 10. In the channels 24, the 50 supplied air and gas are mixed and ignited.

The supply of gas, it may be here stated, may be conveniently regulated or controlled through the medium of any suitable valve (not shown) in the supply tube 23. The air 55 supply through the ports 26 is preferably, however, controlled by means of a slide-valve in the form of an elongated plate 27 working in parallel slide-ways 28 secured on the underside of the floor 9 and cross-connected at intervals throughout their length by arcuate yokes 29. While not specifically shown, the slide-valve plate 27 is provided with a series of apertures that may be respectively brought into full or partial register with the ports 26, so as to regulate the

quantity of air admitted to the chamber A, the plate 27 having an operating-rod 30 attached thereto and extending outside of the oven within convenient reach of an attendant.

It might also be here stated that, according to the length of the chamber A, there may be provided one or more points of application of fuel. In any case, for practical purposes, however, the oven will be of considerable length, and there will ordinarily be two or more points of fuel supply near the forward portion of the structure, and these may be used collectively or separately, depending upon the degree of heat to be maintained and the necessary regulation of the blast.

The side walls of the chamber A are constructed of an outer shell of ordinary insulation brick 31 with a lining 32 of tile composed of fire-brick material, as best seen in Figure 3, and spaced from said side walls is an outer shell or retaining wall composed preferably of sheet metal plates 33 secured at their lower marginal portions to the outer flange of a channel-member 34 extending longitudinally along the bottom portion of the oven and resting on the projecting floor slabs 5. The wall-plates 33 are also bolted to parallel pairs of upstanding supports and reinforcing members 35, in turn, bolted to the projecting end-portions of the transverse floor supports 4. The supports 35 project upwardly a considerable distance above the top of the oven, and, in practice, carry at their upper end a suitably trussed sheltering roof (not shown), which braces them, or they may be obviously braced by any suitable cross-connections or frame-work according to approved structural practices. As also best seen in Figure 3, the space between the brick side-walls and the outer metallic shell of the structure is preferably filled with a body of loose sand 36, which serves as heat-retaining insulation for the chamber A and the air-supply ducts.

B designates the carbonizing and distilling or vaporizing chamber, which is constructed preferably of metal. As shown, channel members 37 are disposed along the tops of the brick side walls of the chamber A and have secured thereto frame-members or yokes 38, which are substantially E-shape in elevation, as seen in Figure 3, and located at intervals corresponding to the positions of the uprights 35, or, in other words, the yokes 38 are preferably in transverse alignment with each pair of the uprights 35. Secured to the upper ends of the yokes 38, are channel members 39, and secured, in turn, to the outer sides of said channel and frame members are plates 40, this structure being cross-connected with the respective uprights 35 by struts 41 comprising sleeves interposed between the outer faces of the plates 40 and the inner sides of said uprights 35 and tie-bolts 42 extending through the sleeves and fastened at their opposite ends by nuts 43, 44, with inter-

posed washers or clamping plates 45, 46, engaging the inner and outer portions, respectively, of the frame members 38 and the uprights 35.

5 Secured to the inner flange of the lower channel members 37, is a longitudinal series of plates 47. A similar series of plates 48 is secured to the upper channel members 39, while fixed on the middle legs 49 of the yoke-members 38, is an intermediate series of plates 50. Said series of plates form division walls between the chamber B and the chambers C formed by the channel-members 37 and 39 and plates 40, the several series of plates being spaced the one from the other and providing longitudinal slots or passages 51, 52, affording continuous communicating openings between the chamber B and the opposed flanking collecting-chambers C so provided by the channel-members 37 and 39 and plates 40 at opposite sides of the chamber B. Preferably the middle series of plates 50 is tilted or obliquely disposed, as shown in Figure 3, to the lower and upper walls or plates 47 and 48, its upper edge portion being offset inwardly from the lower edge of the upper series of plates 48 into the chamber B, and its lower edge portion being correspondingly offset outwardly into the collecting-chamber C. By this arrangement, the plates 49 become, as it may be said, a baffle in effect and function effectively in preventing the products of condensation from entering the chamber B and insure collection of the same in the trough at the bottom of the chamber C afforded by the lower series of plates 47, the channel member 37, and the lower portion of the outer plates 40.

40 The chamber B is covered or roofed by preferably removable plates 54 whose longitudinal edge portions 55 are flanged downwardly over the outer sides of the upper edge portions of the upper longitudinal plates 48, while at their transverse meeting edge portions they are provided with angle members 56 which serve as stiffening reinforcements and afford upstanding flanges, over which latter are placed channel members 57 which serve as seam caps. The cover-plates 54 are 45 further provided with additional angle members 58, which latter are provided with eyes for the engagement of the hooked lower end portions 59 of hanger-bars 60 whose upper end portions are hooked, as at 61, over preferably tubular cross-carrier bars 62 supported, in turn, at their ends on a stable part of the structure, preferably, as shown, on the vapor-conducting mains 63 at opposite sides of the oven, which latter will presently be 50 described.

It may be here stated that the top or roof of the chamber B and the collecting-chamber C is preferably insulated by a sand fill 64 retained at the sides of the structure by the 55 upper marginal portions of the side plates 40,

which latter, in connection with the upper channel members 39, afford troughs at each side of the oven.

The mains 63, of which there is one for each of the collecting-chambers C, are supported at suitable intervals by tubular or pipe-sections 65, which are mounted, as best seen in Figure 3, on the upper channel members 39. This arrangement or mounting of the mains 63, in turn, affords a stable, firm support for the carrier-bars 62, as before stated. The pipes 65 afford direct communication between the collecting-chambers C and the mains 63, preferably each pipe 65 being provided with a suitable valve 66 for controlling the flow or take-off of vapor and lubricant therethrough.

Paralleling the mains 63, are so-called lubricant circulating mains 67, which are suitably secured to the uprights 35 as by U-shape straps 68 whose legs are extended between the respective pairs of the uprights and secured by nuts 69 and interposed washers or clamping-plates 70. At intervals throughout the length thereof, communication is established between the mains 63 and 67 by nippled pipe connections 71 having a controlling valve 72 in each, and on the end of said pipe connections within the suction mains 63 are upwardly directed spray nozzles 73, for purposes shortly appearing. I may here state that, as best seen in Figure 1, the two mains 67, which have suitable connection, not shown, with a source of lubricant or by-product supply under pressure, may be connected, either at the front end or at any other desirable point within the length of the oven or retort, with a common manifold 74 having communication, in turn, with a well, settling-tank, or the like, not shown, for the used lubricant or by-product fluid, and from which such fluid may be removed and suitably treated for resupply to the mains 67. The two mains 63 may also be connected by a common manifold 75, as seen in Figure 1, from which the products delivered by the main 63 may be suitably conducted for treatment for commercial or other use, as may be desired.

The material to be treated is fed into the chamber B at the rear end of the oven or retort and is thence conveyed forwardly on the slabs 14 which constitute and form the roof of the chamber A and the floor of the chamber B, during which time, under the influence of heat transferred by the floor 14, the volatile substances are thrown or driven off, the residue being finally discharged at the front end of the chamber B into a chute 76, through which latter it passes to a suitable conveyor 77 which takes it to the desired place of storage or utilization.

In the distillation and carbonization of material, such, for instance, as bituminous coal, which will now be described, the mate-

rial is first pulverized preferably to such a degree of fineness that the largest particle thereof will pass through a screen or sieve of what is known as "14 mesh" and approximately fifty per cent (50%) thereof will pass through a screen or sieve of "100 mesh". The material, in such finely divided condition, is supplied to a hopper 78 communicating with the rear end portion of the chamber

10 B through a passage way 79 controlled by an adjustable gate 80 which regulates the stream.

In practice, the pulverized material is efficiently carried along the floor of the chamber B in a substantially uniform sheet having a 15 depth of approximately two inches by means of an endless belt conveyor shown in Figures 4 and 6 conventionally and schematically by broken lines in Figures 1 and 2.

Such conveyor comprises parallel endless 20 chain belts 81 which pass over sprocket wheels 82, 83, located at opposite ends of the oven. Power for driving the sprockets may be applied to those at either or both ends of the oven, as may be desired, and as these 25 details constitute no essential part of the present invention, specific illustration thereof is omitted.

Connecting the links 84 of the sprocket 30 chains 81 are pivot-pins or bolts 85, and mounted on the pivot-pins or bolts 85, as best seen in Figures 6 and 7, are peripherally grooved rollers 86 adapted to travel or ride intermediate the driving sprockets 82, 83, upon trackways 87, 88, located within the 35 collecting-chamber C, the lower trackways 87 being mounted on the base portions of the frame-members 38 and the upper trackways 88 being mounted on the middle legs 49 of the frame-members 38.

40 On the inner faces of the inner chain-links 84, about midway their pivot bolts or pins 85, are bosses or lugs 89, in which are secured the end-portions of transverse blade-carriers or shafts 90 preferably in the form of tubular rods, as shown, see Figure 6; and hingedly mounted for swinging movement on the 45 rods or shafts 90, are scrapers 91. As best seen in Figures 6 and 7, each scraper 91 has a hooked end-portion 92 loosely disposed upon a shaft 90 and retained in engagement therewith by means of a cotter-pin or the like 93 passed through both the body and end-portion of the scraper. As also shown in Figure 7, each scraper 91 is retained from 50 shifting longitudinally of its supporting shaft 90 by means of cotter-pins or the like 94 fitted into the shaft upon opposite sides of the scraper.

55 The free end portions of the scraper 91 are flanged downwardly, as at 95, and riveted or otherwise fixed thereto, as at 96, are blades 97. Normally, the blades 97 ride with their lower or scraping edge portions on the floor 14 of the chamber B, and in this relation the 60 blades 97 set at an angle of approximately

thirty degrees with respect to the surface of the floor 14, the inclination being rearward relatively to the direction of travel of the scrapers. Preferably the upper portion 98 70 or each blade 97 is turned at an angle of substantially thirty degrees to the body of the blade and set substantially perpendicular to the surface of the floor 14 in the normal position of the blade.

The blades 97 are of a length to reach in 75 close proximity to the wall plates 47 and 48 of the collecting-chamber C at opposite sides of the oven and are spaced at relative distances from each other so as to move the sheet of pulverized material being treated 80 steadily and evenly along the surface of the floor 14 of the chamber B.

Hence, in use and operation, under the influence of the heat imparted to the floor 14 by 85 the burning gases in the compartments 16 of chamber A and by the floor 14 imparted to the material being fed or scraped therealong by the series of scrapers 91, the volatile portions of such material are vaporized and driven off and under the pressure created in the chamber B and slight suction created in the mains 63 by a suitable pump or other suction creating means, not shown, pass first into the flanking collecting-chambers C and from the 90 chambers C and through the pipes 65 to the collecting mains 63, flowing, in turn, from the mains 63 and the manifold 75 to condensing or other treating apparatus for commercial 95 utilization. Any of such vapors condensing in the chambers C, pipes 65, or mains 63 will flow back or precipitate into the troughs provided by the channel-members 37 and may then for utilization be drawn from the 100 oven in any suitable manner.

105 During such distilling or vaporizing operations, the lubricant or other suitable by-product fluid is suitably pumped into the mains 67 and then sprayed into the mains 63. From the mains 63, the sprayed fluid flows or precipitates through the pipes 65 directly 110 first upon the belts or chains 81, rollers 86, and trackways 87, 88, and then into the troughs provided by the channel members 37, from which the spent fluid may be suitably removed and, under suitable separation process with the condensed vapors, treated for 115 re-use in the oven. By such means, not only are dust troubles within the chambers C and mains 63 largely eliminated without in any manner interfering with or retarding proper take-off of the vapors of distillation, but the moving parts are automatically maintained throughout the operations of the oven in well lubricated condition, thus making for ease 120 of operation and preservation of parts.

125 For convenience in ignition of the fuel gases in the compartments 16 of chamber A and for inspection of the conditions of the chamber from time to time during retort operations, sight-openings 99 are preferably 130

provided in the oven side-walls, which openings are provided with suitable closures to be opened and closed at will. Corresponding openings 100, in alignment with the openings 5 99, may be provided in the division walls 15 for access to and observing the conditions in the innermost compartment or compartments.

I am aware that changes in the form, construction, arrangement, and combination of 10 the several parts of my new retort may be made and substituted for those herein shown and described without departing from the nature and principle of my invention.

Having thus described my invention, what 15 I claim and desire to secure by Letters Patent is:

1. In a retort, a vaporizing chamber, a vapor-collecting chamber flanking the vaporizing chamber, and a wall comprising series 20 of longitudinally disposed plates disposed intermediate the chambers, said series of plates being spaced one from the other and affording communication between the chambers, the intermediate series of plates being disposed 25 obliquely to the upper and lower series of plates.

2. In a retort, a vaporizing chamber, opposed vapor-collecting chambers flanking the opposite sides of the vaporizing-chamber, 30 slotted division walls intermediate the vaporizing-chamber and the collecting-chambers, and a conveyor for feeding the material being treated through the vaporizing-chamber, the conveyor comprising scraper-carriers extending through the slots of said walls and at their ends adapted to travel in 35 the collecting-chambers.

3. In a retort, a vaporizing-chamber, opposed vapor-collecting chambers flanking the opposite sides of the vaporizing-chamber, slotted division walls intermediate said chambers, trackways in the collecting-chambers, and a conveyor for feeding the material being treated through the vaporizing-chamber, said conveyor comprising scraper-carriers extending at their ends through the 40 slots of said walls, and rollers mounted upon the carrier-ends and adapted to travel on said trackways.

50 4. In a retort, a vaporizing-chamber, opposed vapor-collecting chambers flanking the opposite sides of the vaporizing chamber, slotted division walls intermediate said chambers, superposed trackways in the collecting-chambers, and an endless conveyor for feeding the material being treated through the vaporizing-chamber, said conveyor comprising scraper-carriers extending at their ends through the slots of said walls, and rollers mounted upon the carrier-ends and adapted to travel on said trackways.

55 5. In a retort, a vaporizing-chamber, opposed vapor-collecting chambers flanking the opposite sides of the vaporizing chamber, a conveyor for feeding the material being treat-

ed through the vaporizing-chamber, said conveyor having portions extending into the collecting-chambers, and means for delivering a lubricating fluid into the collecting-chambers and upon said conveyor-portions. 70

6. In a retort, a vaporizing-chamber, vapor-collecting chambers flanking the opposite sides of the vaporizing-chamber, trackways in the collecting-chambers, a conveyor for feeding the material being treated in the vaporizing-chamber, said conveyor comprising rollers adapted to travel on the trackways, and means for delivering a lubricating fluid into the collecting-chambers and upon the trackways and rollers. 75

80 7. In a retort, a vaporizing-chamber, vapor-collecting chambers flanking the opposite sides of the vaporizing-chamber, trackways in the collecting-chambers, a conveyor for feeding the material being treated through the vaporizing chamber, said conveyor comprising rollers adapted to travel on the trackways, and means for delivering a lubricating fluid into the collecting-chambers and upon the trackways and rollers, said means comprising mains disposed over the collecting-chambers, communicating pipe-connections between the mains and collecting-chambers, and lubricant supply connections to the mains. 85

90 8. In a retort, a vaporizing-chamber, vapor-collecting chambers flanking the opposite sides of the vaporizing-chamber, a conveyor for feeding the material being treated through the vaporizing-chamber, said conveyor having portions adapted for movement through the collecting-chambers, and means comprising mains having pipe-connection with the collecting-chambers for both receiving the vapor collected in the chambers and delivering a lubricating fluid into said chambers for said conveyor-portions. 100

105 9. In a retort, a vaporizing-chamber, vapor-collecting chambers flanking the opposite sides of the vaporizing-chamber, trackways in the collecting-chambers, a conveyor for feeding the material being treated through the vaporizing-chamber, said conveyor comprising rollers adapted to travel on the trackways, and mains disposed over and having pipe-connection with the collecting-chambers for receiving the vapor collected in said chambers and delivering a lubricating fluid into said chambers for the trackways and rollers. 110

115 10. In a retort, a heating-chamber, a vaporizing-chamber in superposed relation to the heating-chamber, opposed vapor-collecting chambers flanking the opposite sides of the vaporizing chamber, an imperforate wall disposed between and dividing the heating-chamber from the vaporizing-chambers, and slotted division walls intermediate, and providing communication between, the vaporizing-chamber and the collecting-chambers. 125

11. In a retort, a heating-chamber, a vaporizing-chamber in superposed relation to the heating-chamber, the vaporizing-chamber having supply and discharge openings, a wall intermediate said chambers, said wall forming the top of the heating-chamber and the floor of the vaporizing-chamber, means for feeding the material being treated over the floor of and through the vaporizing-chamber from its supply to its discharge opening, a vapor-collecting third chamber flanking the vaporizing-chamber, and an apertured wall disposed intermediate and affording vapor discharging and collecting communication between the vaporizing and third chambers.

12. In a retort, a heating-chamber, a vaporizing-chamber in superposed relation to the heating-chamber, the vaporizing-chamber having supply and discharge openings, a wall intermediate said chambers, said wall forming the top of the heating-chamber and the floor of the vaporizing-chamber, means for feeding the material being treated over the floor of and through the vaporizing-chamber from its supply to its discharge opening, a vapor-collecting third chamber flanking the vaporizing-chamber, and a wall intermediate the vaporizing and third chambers, said wall comprising longitudinal series of plates arranged in superposed spaced relation and affording continuously open vapor discharging and collecting communication between the vaporizing and third chambers.

13. In a retort, a heating-chamber, a vaporizing-chamber in superposed relation to the heating-chamber, the vaporizing-chamber having supply and discharge openings, a wall intermediate said chambers, said wall forming the top of the heating-chamber and the floor of the vaporizing-chamber, means for feeding the material being treated over the floor of and through the vaporizing-chamber from its supply to its discharge opening, opposed vapor collecting chambers flanking the opposite sides of the vaporizing-chamber, and walls dividing said third chambers from the vaporizing-chamber, each of said walls comprising longitudinal series of plates arranged in superposed spaced relation and affording continuously open vapor discharging and collecting communication between the vaporizing and third chambers.

14. In a retort, a heating-chamber, a vaporizing-chamber in superposed relation to the heating-chamber, the vaporizing-chamber having supply and discharge openings, a wall intermediate said chambers, said wall forming the top of the heating-chamber and the floor of the vaporizing-chamber, means for feeding the material being treated over the floor of and through the vaporizing-chamber from its supply to its discharge opening, a vapor-collecting chamber flanking and hav-

ing vapor-collecting communication with the vaporizing-chamber, a vapor-collecting main, and a series of pipe connections providing communication at spaced points between said main and the vapor-collecting chamber.

15. In a retort, a horizontally disposed heating-chamber, a horizontally disposed vaporizing-chamber extending longitudinally the retort in superposed relation to the heating-chamber, the vaporizing chamber having supply and discharge openings at the opposite longitudinal ends of the retort, a horizontally disposed wall intermediate said chambers, said wall forming the top of the heating-chamber and the floor of the vaporizing-chamber, means for feeding the material being treated over the floor of and through the vaporizing-chamber from its supply to its discharge opening, a vapor-collecting chamber also extending longitudinally the retort flanking the vaporizing-chamber, an apertured wall intermediate and providing communication between the vaporizing chamber and the vapor-collecting chamber, and means for delivering, for purposes described, a fluid into the vapor-collecting chamber.

16. In a retort, a heating-chamber, a vaporizing-chamber in superposed relation to the heating-chamber, the vaporizing-chamber having supply and discharge openings, a wall intermediate said chambers, said wall forming the top of the heating-chamber and the floor of the vaporizing-chamber, means for feeding the material being treated over the floor of and through the vaporizing-chamber from its supply to its discharge opening, opposed vapor-collecting chambers flanking opposite sides of and each having vapor-collecting communication with the vaporizing-chamber and means for delivering, for purposes described, a fluid into each of the vapor-collecting chambers.

17. In a retort, a vaporizing-chamber, opposed vapor-collecting chambers flanking opposite sides of the vaporizing chamber, and a conveyer for feeding the material being treated through the vaporizing chamber, said conveyer having portions extending into the collecting chambers.

In testimony whereof, I have signed my name to this specification.

GEORGE McD. JOHNS.
